LIGHTING UNIT MOUNTING

Arnold N. Taylor and Norbert P. Worden, Detroit, Mich., assignors to C. M. Hall Lamp Company, Detroit, Mich., a corporation of Michigan

Application March 15, 1937, Serial No. 131,084

3 Claims. (Cl. 240—41.5)

This invention relates generally to lamps for motor vehicles and refers more particularly to the type designed for use as head lamps.

In the past it has been customary to use electric bulbs in open reflector sub-assemblies as the lighting elements in such lamps. However, at the present time filaments instead of bulbs are being used in hermetically-sealed units which include the reflector and lens. In some instances it is desirable to have a plurality of such units within a single lamp casing. For example, one unit may be used to project a light beam in a horizontal plane, while another unit may be held in a tilted position relative to the first mentioned unit to cause the light beam projected from the second unit to be inclined relative to the beam from the first unit. Therefore, it is an object of the present invention to provide the units in the lamp casing with a mounting that will permit said units to be readily adjusted whereby the beams of light projected from the units may be properly directed.

Other objects, advantages and novel details of construction of this invention will be made more apparent as this description proceeds, especially when considered in connection with the accompanying drawing, wherein:

Figure 1 is a front elevation of a lamp embodying our invention;

Figure 2 is a sectional view taken substantially on the line 2—2 of Figure 1;

Figure 3 is a sectional view taken substantially on the line 3—3 of Figure 1.

Referring now to the drawing, A is the lamp casing, B and C are the hermetically-sealed lighting units, and D is the mounting for said units.

In the present instance the casing A may be of any desired contour and may be mounted in any suitable manner upon a motor vehicle. Preferably the casing A is open at the front thereof and is provided with an inwardly offset flange 1. 2 is a door for the casing sleeved upon the flange 1 and carrying a lens 3 which may be of any suitable construction or design.

The hermetically-sealed units B and C are arranged adjacent each other, preferably side by side, and may be identical in construction but of different sizes. However, it is to be understood that two or more of such units may be employed if desired. Preferably each unit has a shell 4 of heat resisting glass, known in the trade as Pyrex, provided with meeting front and rear walls 5 and 6 and an annular bead 7 at the juncture of said walls. The front wall 5 may constitute a lens with flutes and prisms or may be plain as

desired, while the front face of the rear wall 6 has a coating of suitable material forming a reflector 8. A suitable filament 9 is carried by the rear wall 6 at the center thereof and is provided with suitable electrical terminals 10 for connection with electric conductors (not shown).

The mounting D for the units preferably comprises a pair of cooperating frames 11 and 12 and suitable adjusting screws 13, 14 and 15, respectively. Preferably the outer frame 11 carries the units B and C and is adjustably connected to the inner frame 12 by the screws 13, 14 and 15. As shown, the outer frame 11 has spaced openings 16 and 17, respectively, for receiving the units B and C and is provided at the edges of said openings with rearwardly projecting dished annular flanges 18 and 19, respectively, that embrace and form seats for the beads 1 of the units. 20 are rubber gaskets between said beads 1 and flanges, and 21 are split wire rings engaging suitable grooves in the flanges and retaining the gaskets and units in assembled relation. Preferably the flange 18 is dished in such a way that the unit B will be held thereby in an upright position so that the beam of light projected from said unit will be in a horizontal plane, while the flange 19 is dished at such an angle that the unit C will be held thereby in a tilted position relative to the unit B so that the beam of light projected from said unit C will be inclined relative to the beam from the unit B. The inner frame 12 is welded or otherwise rigidly secured to the offset flange 1 of the casing and is provided at its rear edge with a vertical flange 23 that is substantially parallel with the outer frame 11. The adjusting screws 13, 14 and 15 extend freely through the outer frame 11 and threadedly engage the flange 23 of the inner frame. Coil springs 24 are sleeved on these screws between the frame 11 and the vertical flange 23 of the frame 12 and serve to hold the outer frame 11 in proper position relative to the casing, depending upon the adjustment of the screws 13, 14 and 15. Thus, by adjusting the screws 13, 14 and 15, the outer frame 11 will move and carry the units B and C therewith in unison. For example, by adjusting screw 14, the beams of light projected from units B and C will be raised and lowered; by adjusting screw 13, the beams of light from the units will be tilted to the right; and by adjusting the screw 15, the beams of light from the units will be tilted to the left. In each instance, however, the positions of the units B and C relative to each other

will be maintained while such adjustment is being made.

What we claim as our invention is:

1. A lamp having a casing provided with an opening, a pair of laterally spaced light units in said casing for projecting light rays through said opening, and a common mounting for said units including a pair of cooperating frames, one being fixed in the opening in said casing, the second of said frames being substantially parallel to the first mentioned frame and having dished annular flanges embracing and forming seats for said units, one of said dished flanges being offset relative to the other to hold the unit carried thereby in a tilted position relative to the other unit, and an adjustable connection between the frames independent of the casing permitting the second frame and units carried thereby to be bodily moved relative to the first mentioned frame and casing, including screws extending freely through the second mentioned frame and threadedly engaging the lateral flange of the first mentioned frame, and coil springs sleeved on said screws between said second mentioned frame and the lateral flange of the first mentioned frame, the construction and arrangement of said units and annular flanges being such as to preclude movement of said units relative to each other, while permitting movement in unison of both of said units as aforesaid.
2. A lamp having a casing provided with an opening, a pair of laterally spaced light units in said casing, and a common mounting for said units including a pair of cooperating frames, one being mounted in the opening in said casing and having a lateral flange, the second of said frames being spaced from the lateral flange of the first mentioned frame, said second mentioned frame having dished annular flanges embracing and forming seats for the respective units, one of said dished flanges being offset relative to the other so as to hold the unit carried thereby in a tilted position relative to the other unit, and an

adjustable connection between the frames independent of the casing permitting the second frame and units carried thereby to be bodily moved relative to the first mentioned frame and casing, including screws extending freely through the second mentioned frame and threadedly engaging the lateral flange of the first mentioned frame, and coil springs sleeved on said screws between said second mentioned frame and the lateral flange of the first mentioned frame, the construction and arrangement of said units and annular flanges being such as to preclude movement of said units relative to each other, while permitting movement in unison of both of said units as aforesaid.

3. A lamp having a casing provided with an opening, a pair of laterally spaced light units in said casing for projecting light rays through said opening, and a common mounting for said units including a pair of cooperating frames, one being fixed to said casing, the second of said frames being substantially parallel to the first mentioned frame and having dished flanges embracing and forming seats for said units, one of said dished flanges being offset relative to the other to hold the unit carried thereby in a tilted position relative to the other unit, and an adjustable connection between said frames permitting the second frame and units carried thereby to be bodily moved relative to the first mentioned frame and casing, the construction and arrangement of said units and dished flanges being such as to preclude movement of said units relative to each other, while permitting movement in unison of both of said units as aforesaid.
